UNITED STATES PATENT OFFICE.

THOMAS W. COFER, OF PORTSMOUTH, VIRGINIA.

FLY-FAN.

SPECIFICATION forming part of Letters Patent No. 288,021, dated November 6, 1883.

Application filed April 4, 1883. (No model.)

To all whom it may concern:

Be it known that I, THOMAS W. COFER, of Portsmouth, in the county of Norfolk and State of Virginia, have invented a new and useful improvement in Fly-Fans, of which the following is a full, clear, and exact description, reference being had to the annexed drawings, forming part of this specification.

This invention relates to fly-fans in which 10 an oscillating or a rotating arm is provided with a brush or similar device which is to be moved through the air; and the invention has for its object to secure an increased movement of such brushing device without employing 15 other mechanism for driving it than the movement of the arm.

In the drawings, Figure 1 is an elevation of a fly-fan having two arms, which are adapted to be rotated by clock-work, showing my improvement. Fig. 2 is a side elevation of a hand fly-fan embodying my improvement, and Figs. 3, 4, 5, and 6 are detail views showing modifications.

A indicates a stand, which is to contain a 25 clock mechanism for rotating a vertical shaft, B, which is provided with arms C, having flexible joints D. At the outer ends of the arms are provided axles E, on which are mounted wind-wheels F, adapted to be rotated by the action of the air on the blades G as the arms are made to revolve by the clock-work.

The wind-wheel F is preferably formed of a 35 series of clamps, H, supported on a hub, ring, or disk, and flexible blades G, made of paper or other suitable material, which are held in position by the clamps. As shown in Fig. 2, the clamps may be arranged in one and the same plane, so as to hold the blades in such 40 plane, to the end that the latter may be deflected to either side of said plane by the oscillation of the wheel through the air in the direction of its axis. This construction adapts the wheel for use in a hand fly-fan, the movement of the arm I to and fro through the air serving to rotate the wheel continuously in 45 one direction.

In the case of the fan which is run by clock-

work, it is unimportant that the blades should be of flexible character if the clamps are set obliquely, as shown in Fig. 1, and the wind-wheels intended for such use may be formed with the clamps so arranged, or made adjustable, so as to be set in such position when desired. The only advantage of setting the clamps obliquely with respect to the plane of the wheel is that no additional force will be required for deflecting the blades in such case, and the wheels may be rotated with a very slow movement of the arms. In a hand brush or fan a more rapid and forcible movement may be given to the arm carrying the wheel, and in such case the wheel having the blades set in one and the same plane is indispensable where a continuous movement is desired.

I do not confine myself to either of the special forms of wheels above described, since the construction may be varied at will, as shown in Figs. 3, 4, 5, and 6, without losing any of the advantages set forth.

The clamps are preferably formed by doubling a strip of soft metal upon itself, and the metal may be struck up, as shown at J, to form a recess for accommodating a fold of the paper blade, to prevent the latter from coming out accidentally.

The blades may be perforated or cut away to lessen the degree of resistance to the air.

What I claim is—

1. The combination, with the arm of a fan or brush, of a wind-wheel having blades of flexible material set in one and the same plane, whereby the blades may be deflected to either side of said plane, according to the movement of the arm, substantially as and for the purpose specified.

2. The combination, with the arm of a fan or brush, of a wind-wheel having a series of clamps, and blades formed of strips of flexible material secured by the clamps, substantially as shown and described.

THOMAS W. COFER.
